UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING-MACHINE.

1,356,158.

Specification of Letters Patent. Patented Oct. 19, 1920.

Application filed May 16, 1919. Serial No. 297,655.

To all whom it may concern:

Be it known that I, ALFRED G. F. KUROWSKI, a subject of the Emperor of Germany, or a citizen of Germany, but having taken 5 out preliminary United States naturalization papers, residing in Brooklyn borough, in the county of Kings, city and State of New York, have invented certain new and useful Improvements in Typewriting-Machines, of which the following is a specification.

This invention relates to typewriting machines, and more particularly to tabulating mechanism for such machines.

15 The main object of my invention is to provide a tabulating device simple and effective in form and readily settable for different requirements.

The invention is illustrated as applied to 20 a typewriting machine of the Underwood type. In the present construction, depression of the tabulator key will cause release of the escapement mechanism, and also serve both to move a column-stop bar at the front 25 of the machine to a position to enable the column-stops thereon to coöperate with a counter-stop mounted on the front of the carriage, and to move a brake bar into engagement with a friction member support- 30 ed on the front of the carriage.

In the present embodiment the movement 35 of the column-stop bar is effected by rocking the shaft carrying said bar by means of a slotted arm fixed on said shaft, and a bent link connected at one end with the tabulator lever, and at the other end to said arm by means of a pin entering a slot of said slotted arm, and a forked or slotted end of 40 said link embracing said shaft. Upon depression of the tabulator key the pin on the link will tend to move outward in the slot of the slotted arm, and such outward movement may be controlled by giving a suitable inclination to the slot in the upper end of 45 the link. Provision is made of suitable spring means to return said slotted lever to normal position.

In order to facilitate the setting of column-stops in accordance with the indications of the pointer on a letter-space scale, the pointer is provided with an opening immediately over the column-stop bar when in 50 normal position to enable insertion of a

stop, and with guiding devices associated with said opening to insure proper position- 55 ing of said column-stops.

Provision is made of a pivotally supported cover normally extending over the column-stop bar and pointer, but cut away at its forward edge to enable passage of the 60 pointer between the scale and the cover. The movement of the cover may be limited by a pin-and-slot connection with the frame of the machine, and the cover may be held in raised or lowered position by a leaf spring 65 fixed on the frame of the machine, and a suitably shaped coöoperating member connected with the cover.

Other features and advantages will hereinafter appear.

70 In the accompanying drawings,

Figure 1 is a diagrammatic side elevation, partly in section, of an Underwood typewriting machine with my invention applied thereto.

75 Fig. 2 is a side view in section, showing some of the parts in positions different from those shown in Fig. 1.

Fig. 3 is a fragmentary perspective view 80 of the tabulating mechanism at the front of the machine, the cover being raised.

Fig. 4 is a view showing the pointer, and so much of the column-stop bar and scale as is necessary to show the relation therebetween.

85 Upon depression of character keys 1, type-bars 2 will be swung upwardly and rearwardly, to bring types thereon in contact with a work-sheet on a platen 3 revolvably supported in a platen frame 4 mounted 90 for movement in a carriage 5. Said carriage 5 is mounted on front and rear rails or bars 6 and 7, respectively, and is urged in one direction by a strap 8 and spring-drum 9. In order to control the movement 95 of said carriage 5 under the influence of spring-drum 9, a rack 10, pivotally supported on carriage 5 by means of arms 11, normally engages with a pinion 12 having a usual one-way connection with escape- 100

ment wheel 13, which is controlled by the usual fast and loose dogs 14 and 15, respectively. Said fast and loose dogs are normally held in forward position, but are moved to the rear by means of a universal 105 frame 16, which is struck by a heel 17 on a

type-bar 2 at the end of the printing stroke of the type-bar.

When a tabulating movement is desired, tabulator key 18 is depressed and acts 5 through tabulator lever 19 pivoted on shaft 20 and urged to normal position by means of spring 21, to actuate link 22, arm 23, arm 24 and bent link 25 to rock lever 26 pivoted at 27, and thereby raise rack 10 from engagement with pinion 12 by means of a wheel 28 mounted on said lever 26. The mechanism so far described is well known in connection with the Underwood type-writing machines.

10 To connect lever 19 with the tabulating mechanism at the front of the machine, provision is made of link 29 pivoted to lever 19 by means of a shouldered screw 30, and connected to a lever 31, by means of which 15 a rack bar or column-stop bar 32 carrying column-stops 33 is moved into position to coöperate with counter-stop 34 mounted at the front of the carriage. Concomitantly with the movement of bar 32, a bar 35 is 20 moved into contact with a friction device or pad 36 supported on the carriage immediately above said counter-stop. The bar 35 and friction device 36 constitute means 25 for controlling the movement of the carriage when the escapement mechanism is 30 rendered ineffective.

In order to obtain satisfactory movement of the parts of the tabulating mechanism when actuated by a tabulating lever 19, lever 31 is provided with a slot 37 at its 35 rear end, and link 29 is provided with a pin 38 having threaded engagement therewith and engaging in slot 37, and at its upper end with a forked portion embracing shaft 39 on which lever 31 is mounted. Rack bar 32 and bar 35 are supported at one 40 side of the machine by lever 31, and at the other by an arm 40 secured to shaft 39. A leaf spring 31^a secured to lever 31 and en- 45 gaging rail 6 serves to return lever 31 and the associated parts to normal position. It will be seen that depression of link 29 will tend to move pin 38 to the outer end of slot 37, and that such movement is con- 50 trolled in accordance with the inclination of the slot in the forked end of link 29, the shaft 39 and the forked end of link 29 co-operating to effect a camming action.

The tabulating mechanism at the front of 55 the machine is normally covered by means of a cover 41 pivoted at 42 and 43 on the frame, the movement of the cover being limited by a pin-and-slot connection shown at the right of Fig. 3. When in closed position, the forward edge of cover 41 rests on the main frame at opposite ends of letter-space scale 44, and said cover 41 is provided at each end of its forward edge with projections 45 which serve to space the cover 60 from the bar-carrying scale 44 to enable the

passage therebetween of the tip of pointer 46 fastened to the carriage immediately above friction device 36.

70 Preferably at the right of the machine, cover 41 is attached to a member 47, which serves to connect the cover with the pivot 43. Pivotal movement of member 47, and consequently of cover 41, is limited by suitable means, such as a pin 48 mounted in the frame and projecting into a slot 49 in member 47, said slot being concentric with pivot 43.

75 Provision is also made of a spring 50, supported at one end on the frame and having its free end in contact with member 47, the coöperating curved surface 51 of which is convex to such an extent that the central portion is at a greater distance from the pivot 43 than are the end portions, which are provided with notches 52 and 53, with 80 which the bent end of spring 50 engages 85 with the cover in closed and open positions, respectively. It will be seen that the structure just described will prevent rattling of the cover when in closed position. 90

Immediately above the position assumed by the bar 32 under normal conditions, the pointer 46 is provided with an opening 54 of sufficient size to enable insertion therethrough of a column-stop 33 held between the thumb and forefinger, and lugs 55 are provided at the front and back of said opening to serve as guides, by means of which the column-stops may be properly positioned on the column-stop bar. The clearance between pointer 46 and bar 32 is such that no interference will result when the column-stop bar is swung to rearward position. 95

100 Variations may be resorted to within the scope of the invention, and portions of the improvements may be used without others. 105

Having thus described my invention, I claim:

1. In a typewriting machine, the combination with a letter-space scale, of column-stops, a column-stop rack, a member including a counter-stop to coöperate with said column-stops, means to effect a relative traveling movement between said member and both said scale and said rack, a pointer to 110 coöperate with said scale secured to said member and having an opening therethrough above said rack, and guiding devices positioned oppositely with reference to said opening, whereby a column-stop inserted therethrough will be positioned on said rack in accordance with the indication of said pointer on said scale. 115

2. In a typewriting machine, the combination with a traveling carriage, of a line-space scale at the front of the machine, and tabulating mechanism for said carriage including a column-stop rack positioned between said scale and the front of the carriage, a pointer secured to said carriage and 125 130

- extending across said rack to coöperate with said scale, and guiding means associated with said pointer to direct a column-stop to a position on said rack in accordance with 5 the indication of said pointer on said scale.
3. In a tabulator for typewriting machines, the combination with two members and means to effect a letter-feed traveling movement therebetween, of a letter-space 10 scale on one of said members, a pointer on the other of said members to coöperate with said scale to indicate the relative position of said members, column-stops, a column-stop bar, adapted to receive said column- 15 stops at letter-space intervals, extending beneath said pointer, means to prevent a letter-feed movement between said scale and said column-stop bar, and guiding means associated with said pointer whereby a column- 20 stop may be set on said column-stop bar in accordance with the indication of said pointer.
4. In a typewriting machine, the combination with a letter-space scale, of column- 25 stops, a column-stop rack, a member including a counter-stop to coöperate with said column-stops, means to effect relative traveling movement of said member and both said scale and said rack, and a pointer to co- 30 operate with said scale, said pointer having guiding means thereon to guide a column-stop into position on said rack in accordance with the indication of said pointer on said scale.
5. In a typewriting machine, the combination with a traveling carriage, of a letter-space scale at the front of the machine, a column-stop bar between said scale and the front of said carriage, a counter-stop on 40 the front of said carriage, means to move said column-stop bar to enable coöperation of column-stops thereon with said counter-stop, and a pointer on said carriage to coöperate with said scale, the configuration of 45 said pointer being such as to enable a column-stop to be set on said bar at a point opposite the division of the scale indicated by said pointer.
6. In a typewriting machine, the combination 50 with a traveling carriage, of tabulating means therefor comprising a rock shaft, a column-stop bar adapted to receive column-stops at letter-space intervals mounted on said shaft, a counter-stop on said carriage, 55 and means for rocking said shaft to bring said bar into position to enable coöperation between column-stops mounted on said bar and said counter-stop, including a slotted arm mounted on said shaft, a tabulating 60 lever, a link connected with said tabulating lever, a member on said link extending into the slot of said slotted arm, and cam means to determine the position of said member in the slot of said slotted arm.
7. In a typewriting machine, the combi- 65 nation with a traveling carriage, means urging said carriage in letter-feeding direction, and an escapement mechanism to control the movement of said carriage, of a rock shaft at the front of the machine, a rack 70 supported on said shaft, column-stops adjustably positioned on said rack, a counter-stop on said carriage, and means for swinging said rack into position to enable coöperation between said column-stops and said 75 counter-stop, and to concomitantly release said escapement mechanism, including a slotted arm secured to said shaft, a bent link having a pin entering the slot of said slotted arm, and a slotted end to embrace said 80 shaft, and a tabulating lever connected with said link.
8. In a typewriting machine, the combination with a traveling carriage, of tabulating means therefor, comprising a rock-shaft, 85 a column-stop bar adapted to receive column-stops at letter-space intervals mounted on said shaft, a counter-stop on said carriage, and means for rocking said shaft to bring said bar into position to enable coöperation 90 between column-stops, mounted on said bar, and said counter-stop, including a slotted arm mounted on said shaft, a tabulating lever, a link connected with said lever, having a member thereon extending into the 95 slot of said slotted arm, and a forked end embracing said rock-shaft, said forked end being adapted to control the movement of said member in the slot in said slotted arm.
9. In a typewriting machine, the combination 100 with a traveling carriage, of a letter-space scale at the front of the machine, a pointer on the front of said carriage to coöperate with said scale, a column-stop bar between said scale and the front of said carriage, column-stops mounted thereon, a counter-stop on the front of said carriage beneath said pointer, and means to move said column-stop bar into position to enable coöperation of the stops thereon with 105 the counter-stop.
10. In a typewriting machine, the combination 110 with a traveling carriage, of a letter-space scale at the front of the machine, a pointer on the front of said carriage to coöperate with said scale, a column-stop bar between said scale and the front of said carriage, column-stops mounted thereon, a counter-stop on the front of said carriage beneath said pointer, a brake device comprising a friction member on said carriage adjacent said counter-stop, and a brake bar extending across the machine, and means to move said column-stop bar into position to enable coöperation of the column-stops 120 thereon with the counter-stop, and concomitantly move said brake bar into engagement with said friction member.
11. In a typewriting machine, the combi- 125 nation with a traveling carriage and 130

ing means therefor, including a front rail, of tabulating mechanism comprising a rock-shaft at the front of the machine, a column-stop bar supported on said shaft, column-
5 stops on said column-stop bar, a counter-stop on said carriage, a slotted arm secured to said rock-shaft, a link having a member thereon entering the slot of said slotted arm, and a cam-slotted portion to embrace said
10 shaft, a tabulating lever connected with said link, and a leaf spring fixed on said slotted arm and engaging said front rail to urge said rock-shaft to its normal position.

12. In a typewriting machine, the combination with a traveling carriage, of a bar fixed on the frame of the machine and extending across the front thereof, a letter-space scale on said bar, a pointer on said carriage to coöperate with said scale, tabulating mechanism including a pivotally mounted column-stop bar lying between said carriage and said scale, column-stops thereon, a counter-stop on said carriage, means to move said column-stop bar into effective relation with respect to said counter-stop, a cover pivoted to said frame at its rear edge, and means whereby the forward edge of said cover will be spaced from said fixed bar to permit passage of the pointer therebetween.
15

13. In a typewriting machine, the combination with a traveling carriage, of a bar fixed on the frame of the machine and extending across the front thereof, a letter-
20 space scale on said bar, a pointer on said
25

30

carriage to coöperate with said scale, tabulating mechanism including a pivotally mounted column-stop bar lying between said carriage and said scale, column-stops thereon, a counter-stop on said carriage, 40 means to move said column-stop bar into effective relation with respect to said counter-stop, a cover pivoted at its rear edge to said frame, means whereby the forward edge of said cover will be spaced from said fixed bar 45 to permit passage of the pointer therebetween, and means for yieldingly holding said cover in open and closed positions.

14. In a typewriting machine, the combination with a traveling carriage and an escapement mechanism therefor, of a tabulator-lever, tabulator-lever-actuated means for releasing said carriage from the control of said escapement mechanism, a rock-shaft mounted at the front of the machine, a stop-carrying rack-bar, a friction bar supported by arms fixed on said rock-shaft, stop-carrying means, a friction member supported on the front of the carriage, and connections between said tabulator-lever and said rock-shaft whereby, upon depression of said tabulator-lever, said rack-bar will be positioned with a stop thereon in position for engagement with a stop on said stop-carrying means, and said friction bar will be caused 55
60
65 to engage said friction member.
